UNITED STATES PATENT OFFICE.

RICHARD A. WAGSTAFF, OF SALT LAKE CITY, UTAH, ASSIGNEE TO AMERICAN SMELTING AND REFINING COMPANY, OF NEW YORK, N. Y., A CORPORATION OF NEW JERSEY.

BLAST-FURNACE TUYÈRE CAP FOR PULVERIZED COAL.

1,415,910.

Specification of Letters Patent.

Patented May 16, 1922.

Application filed March 15, 1920. Serial No. 365,829.

To all whom it may concern:

Be it known that I, RICHARD A. WAGSTAFF, a citizen of the United States and resident of Salt Lake City, in the county of Salt Lake 5 and State of Utah, have invented certain new and useful Improvements in Blast-Furnace Tuyère Caps for Pulverized Coal, of which the following is a specification.

The invention relates in general to an improved form of tuyère constituting a part of a blast furnace of the type used in metallurgical operations and particularly relates to a closing cap, and associated parts, for use in connection with the conventional forms of 15 tuyères usually employed with such furnaces.

In metallurgical furnaces it is at present known to provide one or a plurality of tuyères for supplying the charge in the furnace with air and under some conditions to 20 supplement this air with a charge of carbonaceous fuel, such as coal. Under some conditions this coal is ejected into the furnace through an ejector and forced into the furnace in the form of a cloud under the propelling force of a relatively high pressure 25 air.

One of the objects of the invention is to provide a supplemental fuel feeding tube as a discharge tube from the usual ejector and 30 to dispose this discharge tube in positions in a tuyère so as to utilize the relatively low pressure air fed through the tuyère to supplement the ejector effect upon the fuel forced into the furnace by the usual ejector. 35 The invention contemplates, primarily, the utilization of a closing cap for the tuyère which cap in addition to closing the tuyère constitutes the support for the supplemental feed tube featured in this disclosure.

40 Considering the closing cap feature of the disclosure another object of the invention is to provide a simple means for securely mounting the fuel feed tube in position in the cap and for mounting the same in such 45 a way that it can be removed without removing any part of the cap.

Another object of the invention is to provide a cap which will permit an inspection of the interior of the furnace or of the 50 tuyère at the point where the fuel supplying tube is discharging its contents and to permit access to the furnace without creating an opening which would cause the loss of any material amount of coal dust.

Still another object of the invention is to 55 provide a simple design of cover which can be readily assembled or demounted and in which a readily actuated gate closes the opening through the cap.

Various other objects and advantages of 60 the invention will be in part obvious from an inspection of the accompanying drawings and in part will be more fully set forth in the following particular description of one form of mechanism embodying my invention, and the invention also consists in certain new and novel features of arrangement and combination of parts hereinafter set forth and claimed.

Figure 1 is a view in vertical section of a 70 portion of a furnace at one of the tuyères equipped with a preferred embodiment of the invention and taken on the line 2—2 of Figure 2;

Figure 2 is a view in front elevation of the 75 cap shown in Figure 1;

Figure 3 is a similar view of the rear plate;

Figure 4 is a view in side elevation of the 80 device shown in Figure 2; and

Figure 5 is a medial vertical sectional view 85 of the rear plate similar to the showing of this member in Figure 1 but separated by its associated parts.

In the drawings there is shown a double 85 wall furnace 10 with the walls spaced apart to provide the usual water jacket space 11. The furnace is provided with an intake port 12 extending into the interior 13 of the furnace. The port or opening 12 is outlined 90 on the outer side of the furnace by the usual tuyère plate 14 to which is attached a tuyère 15 of conventional form. The tuyère is provided with the usual air conduit 16 for supplying the furnace with low pressure air. 95 The tuyère is provided as usual with a pair of oppositely disposed openings 17 and 18, the former of which aligns with the opening 12 and constitutes a straight continuation thereof leading to the furnace interior. 100 The outer opening 18 is closed by means of a built up cap 19 particularly constituting the subject-matter of this disclosure. The cap is formed mainly of two abutting plates, a rear plate 20 and a face plate 21 demountably fastened one to the other by means of screws 22 accessible from the front side of the cap. The base plate is provided with a

pair of laterally extending wings 23 which fit behind lugs 23' projecting forwardly from the front of the tuyère body. The base plate is provided with two vertically spaced 5 apart holes 24 and 25 and is provided on the lower portion of its front side with an upwardly extending recess forming a gateway 26. A pair of legs 27 constitute downwardly extending extensions which are provided on their lower ends with inturned 10 flanges 28 constituting a supporting ledge for the gate 29 hereinafter more particularly described.

The face plate 21 is provided with three 15 vertically disposed openings extending therethrough, the upper opening 30 being slightly larger in diameter than the opening 24, concentrically disposed relatively thereto and coaxing with the opening in the base plate 20 to form a feed pipe containing opening through the upper portions of the cap.

The base plate is provided with an annular lug receiving recess 31 which encircles the opening 24 and one portion of which recess is deepened and enlarged diametrically 25 to form an arcuate slot 32. The face plate is also provided with a dove-tail-shaped opening facing the slot 32 but of less circumferential extent so as to provide a 30 bayonet joint for a lug 34 projecting laterally from a locking nut 35. The locking nut is mounted in the opening 30 with its inner end abutting against the recessed portion of the base plate.

35 The front side of the lug 34 is bevelled as shown at 36 and this bevel side is designed to engage the rear side of the face plate, so that, when the lug is rotated from the exposed part 33 of the recess 32 circumferentially into the dotted line position 40 shown in Figure 2, the nut 35 will be wedged securely into set position in the cap. The nut is provided with an internally threaded bore. A supplemental ejector pipe 37 has 45 one end screwed into the inner end of the bore and has its discharge end 38 positioned within the opening 17 and beyond the conduit 16 in the tuyère. Threaded into the outer end of the bore in the nut is a discharge tube 40 from an exteriorly positioned 50 ejector 41. This exteriorly positioned ejector is of conventional Y-form having a bell 42 connected with a supply of carbonaceous fuel, such as coal, admitted thereto through 55 the flexible tubing 43. The ejector is also provided with an ejector tube 44 connected at its outer end with a source of high pressure air indicated symbolically by the flexible tubing 45 and the opposite discharge end 60 46 of which is arranged axially in the ejector in position to discharge the cloud of coal through the discharge tube 40. It is understood that this ejector is of conventional form and the organization disclosed differs 65 from known forms in the forming of the

discharge tube in two parts in the supporting of the same by the cap and in the positioning of the discharge end beyond the air conduit in the tuyère so as to take advantage of the low pressure air to supplement the ejector 70 feature of the usual form of ejectors which discharge directly into the tuyère or furnace.

The middle opening 47 in the face plate aligns with the opening 25 in the base plate 75 and coacts therewith to provide a hole clear through the cap and which hole can be utilized either to view the interior of the furnace at the point where the supply of fuel is being ejected thereto by the discharge 80 nozzle 38, or may be used to introduce a poke tool into the furnace and for this latter reason this opening will be identified herein-after as a poke hole. The hole is designed to be closed by means of a gate 29 which is 85 shown to have a bevelled upper portion 48 which bevelled portion has a wedging fit in the gateway and is designed to be held elevated in position closing the poke hole by means of a pin 49 insertable through the 90 lowermost hole 50 in the face plate and passed through an aligned pin hole 51 in the body of the gate. The gate has its lower portion reduced to form shoulders 52 which engage the flanges 28 and support the gate 95 in opened position uncovering the poke hole. The lower end of the gate is provided with a forwardly extending flange 53, constituting an exposed finger piece for raising the gate or for hammering the gate into open 100 position in case it should become stuck in its elevated position.

In operation and assuming that the parts are in the position indicated in Figure 1, the device is in position for active operation. The air is admitted through the conduit 16 and passes into the interior of the furnace through the opening 12 as is usual. At the same time and with the ejector in active operation, the pulverized coal is ejected 110 forcibly through the ejector tube 44 by means of the high pressure air admitted through the tube 45 and this fuel charge is ejected from the nozzle 38. It is further diffused at the entrance to the furnace by 115 the action of the low pressure air passing to the furnace from the conduit 16. The length of the tube 37 is varied so as to bring the discharge nozzle 38 into a position to discharge the fuel into the tuyère body but 120 in relatively close proximity to the interior of the furnace and in such a position as to take advantage of the inflowing air from the tuyère.

By withdrawing the pin 49 the gate can 125 be lowered and thus permit the inspection of the interior of the tuyère through the cap. In this way the opening 12 and the adjacent portion of the interior of the furnace are visible through this peep hole. This hole 130

- is made sufficiently large to accommodate a poke tool and such a tool can be introduced through the hole so as to break up any accumulations in the opening 12. However, 5 it is to be understood that this poke hole is of small dimension, a hole of about one-inch diameter having been found to be sufficiently large and but little fuel or gas can escape from such a small hole.
- 10 The gate can be knocked into closed position and the re-insertion of the pin will secure the gate against any accidental falling into an opening position.
- By means of a device of this character it 15 is possible to permit the operator to look inside the tuyère while the carbonaceous fuel is being admitted and thus provide for an accurate control during the entire blow.
- The operator can punch open the tuyère 20 without removing any part of the cap and thus cut down the amount of coal dust which might otherwise escape into the atmosphere. The bayonet lock connection provided between the locking nut carrying 25 the fuel ejector discharge pipe permits of a ready disconnection between the coal injector and the tuyère without affecting use of the cap as a closure means. Should it be desired to permanently close the opening 30 for the ejector pipe, it is of course possible to substitute a solid nut for the bored locking nut disclosed.
- The positioning of the coal discharge nozzle inside of the tuyère and beyond the 35 down-coming air therein allows this down-coming air to have an ejector effect upon the previously ejected fuel supplied through the external ejector.
- Having thus described my invention, I 40 claim:
1. In a furnace structure, the combination of a furnace provided with a tuyère body in communication with the interior of the furnace, said body provided with an opening on 45 the side thereof opposite the furnace, a cap for closing said opening, a feed tube for conducting fuel to the furnace, said tube carried by the cap, extending therethrough and through said opening into the interior 50 of the tuyère body, easily separable means for securing the tube to the cap and for permitting the ready dismantling of the tube from the cap, said tube being removable as a unit with the cap.
  - 55 2. In a furnace, the combination of a furnace provided with a tuyère body having oppositely disposed openings to permit a view into the interior of the furnace, a cap for closing the outer of said openings, a fuel feeding tube carried by the cap and extending therethrough towards the furnace to supply the same with fuel, and said cap provided with a hole for viewing the discharge of the feed tubes from a point exteriorly 60 of the furnace.
  3. In a furnace, the combination of a furnace provided with a tuyère body having oppositely disposed openings to permit a view into the interior of the furnace, a cap for closing the outer of said openings, a fuel feeding tube carried by the cap and extending therethrough towards the furnace to supply the same with fuel, and said cap provided with a hole for viewing the discharge of the feed tubes from a point exteriorly 65 of the furnace and a gate for closing said hole.
  4. In a furnace, the combination of a furnace provided with a tuyère body having oppositely disposed openings to permit a view into the interior of the furnace, a cap for closing the outer of said openings, a fuel feeding tube carried by the cap and extending therethrough towards the furnace to supply the same with fuel, and said cap provided with a hole for viewing the discharge of the feed tubes from a point exteriorly 70 of the furnace and a gate for closing said hole.
  5. In a metallurgical furnace structure, the combination of a furnace, a tuyère body opening into the same and a closing cap for the tuyère body, said cap provided with means for introducing substances through 75 the tuyère body and into the furnace and also provided with a poke hole for permitting access to, or a view of, the furnace at the place where the substance is being admitted to the furnace.
  6. A tuyère body provided with an opening on one side, a cap for closing said opening, a feed tube extending through the cap into the interior of the tuyère body, said cap provided with a poke hole communicating 80 with the opening in the tuyère body.
  7. A tuyère body provided with an opening on one side, a cap for closing said opening, a feed tube extending through the cap into the interior of the tuyère body, said cap provided with a poke hole communicating 85 with the opening in the tuyère body and a gate for closing the poke hole.
  8. A tuyère body provided with oppositely disposed openings one of which is designed to face and open into the furnace, a cap for closing the other opening, a fuel feed pipe carried by the cap, extending therethrough and across the interior of the tuyère body, said feed pipe provided with a fuel discharging end positioned adjacent the opening which is facing the furnace.
  9. A cap for a tuyère body opening, comprising a base plate provided with means for securing the same to the tuyère body and provided with an opening extending therethrough and having an arcuate slot partially encircling said opening, a face plate contacting with the base plate and having an opening aligning with the opening in the base 100

plate and coating therewith to receive a feed pipe, a portion of the face plate overlapping the arcuate slot to form a bayonet slot and a lock nut adapted to hold the feed pipe in place and provided with a lug adapted to be rotated into locked position in said bayonet slot.

10. A cap for a tuyère body opening, comprising a base plate provided with means for securing the same to the tuyère body and provided with an opening extending therethrough and having an arcuate slot partially encircling said opening, a face plate contacting with the base plate and having an opening aligning with the opening in the base plate and coating therewith to receive a feed pipe, a portion of the face plate overlapping the arcuate slot to form a bayonet slot and a lock nut adapted to hold the feed pipe in place and provided with a lug adapted to be rotated into locked position in said bayonet slot, said base and face plates provided with aligned openings forming a poke hole spaced from the feed pipe openings.

25. 11. A cap for a tuyère body opening, comprising two plates each having a pair of aligned openings extending therethrough, a feed pipe extending through one of the pair of openings and the other pair constituting a poke hole, a gate fitted between the plates to close the poke hole and means for demountably securing the plates together.

30. 12. A cap for a tuyère body opening, comprising two plates each having a pair of aligned openings extending therethrough, a feed pipe extending through one of the pair of openings and the other pair constituting a poke hole, a gate fitted between the plates to close the poke hole and means for demountably securing the plates together, the outer plate provided with a pin hole and a pin adapted to be inserted into said pin hole to engage the gate and to hold the same in position closing the poke hole.

45. 13. A cap for a tuyère body opening, comprising two plates each having a pair of aligned openings extending therethrough, a feed pipe extending through one of the pair of openings and the other pair constituting a poke hole, a locking nut containing the feed pipe and fitted between the plates and means for securing the plates together with a portion of the lock nut secured therebetween.

50. 14. In a blast furnace, a closing cap provided with two openings extending therethrough a pipe for feeding fuel to the furnace demountably secured in one of said openings and the other opening constituting a poke hole permitting access to the interior of the furnace.

55. 15. In a blast furnace, a closing cap provided with two openings extending therethrough a pipe for feeding fuel to the furnace demountably secured in one of said

openings and the other opening constituting a poke hole permitting access to the interior of the furnace and a gate demountably secured to the cap to close the poke hole.

16. In a blast furnace, a closing cap provided with an opening extending therethrough constituting a poke hole permitting access to the interior of the furnace and a gate for closing the poke hole.

17. In a blast furnace, a closing cap provided with an opening extending therethrough constituting a poke hole permitting access to the interior of the furnace, a gate for closing the poke hole, said gate being normally free to fall by gravity and means for locking the gate in position to close the poke hole.

18. In a blast furnace, a closing cap provided with an opening extending therethrough constituting a poke hole permitting access to the interior of the furnace, a gate for closing the poke hole, said gate having a bevelled side for engaging a similar surface on the cap and a pin passed through the cap and gate for holding the gate in position closing the poke hole.

19. A closure cap for a tuyère body comprising a base plate having two openings extending therethrough and a beveled gateway extending from the bottom edge across the lower of the openings, said plate also provided with a lug receiving recess partially encircling the upper opening, a face plate provided with three openings extending therethrough, two of said openings aligning with the two openings in the base plate to form a feed pipe opening and a poke hole opening through the cap the third opening in the face plate being positioned below the base plate a gate fitted in said gateway and a pin in said third hole to hold the gate in place closing the poke hole.

20. A closure cap for a tuyère body comprising a base plate having two openings extending therethrough and a beveled gateway extending from the bottom edge across the lower of the openings, said plate also provided with a lug receiving recess partially encircling the upper opening, a face plate provided with three openings extending therethrough, two of said openings aligning with the two openings in the base plate to form a feed pipe opening and a poke hole opening through the cap, a gate fitted in said gateway and a pin in said third hole to hold the gate in place closing the poke hole and a feed pipe holding nut mounted at the feed pipe opening and provided with a locking lug engaging in said lug receiving recess to secure the nut in place.

21. A closure cap for a tuyère body comprising a base plate having two openings extending therethrough and a beveled gateway extending from the bottom edge across the lower of the openings, said plate also pro-

- vided with a lug receiving recess partially encircling the upper opening, a face plate provided with three openings extending therethrough, two of said openings aligning 5 with the two openings in the base plate to form a feed pipe opening and a poke hole opening through the cap, a gate fitted in said gateway and a pin in said third hole to hold the gate in place closing the poke hole, 10 a feed pipe holding nut mounted at the feed pipe opening and provided with a locking lug engaging in said lug receiving recess to secure the nut in place and a two part fuel feeding pipe with an end of each screwed 15 into opposite ends of said holding nut.
22. In a device of the class described the combination of a furnace, a tuyère body provided with an air conduit for supplying air to the furnace, an ejector positioned 20 exteriorly of the tuyère body and having a discharge pipe positioned with its discharge end adjacent the furnace and in advance of the air conduit in the tuyère body thereby to cause the ingoing air from the conduit to have an ejector effect on the substance discharged from the exteriorly positioned ejector.
23. In a device of the class described the combination of a furnace, a tuyère body provided with an air conduit for supplying air 30 to the furnace, an ejector positioned exteriorly of the tuyère body and having a discharge pipe positioned with its discharge end adjacent the furnace and in advance of the air conduit in the tuyère body thereby 35 to cause the ingoing air from the conduit to have an ejector effect on the substance discharged from the exteriorly positioned ejector, a high pressure air conduit and a pulverized coal conduit leading to said 40 ejector.

Signed at Garfield in the county of Salt Lake and State of Utah this 26th day of February, A. D. 1920.

RICHARD A. WAGSTAFF.
